UNITED STATES PATENT OFFICE.

CLARENCE CANFIELD STIRLING, OF HARTFORD, CONNECTICUT, ASSIGNOR
TO CHARLES E. DUSTIN, OF SAME PLACE.

SWITCH FOR ELECTRIC CIRCUITS.

SPECIFICATION forming part of Letters Patent No. 398,288, dated February 19, 1889.

Application filed June 21, 1887. Serial No. 241,978. (No model.)

To all whom it may concern:

Be it known that I, CLARENCE CANFIELD STIRLING, a citizen of the United States, residing at Hartford, in the county of Hartford and 5 State of Connecticut, have invented certain new and useful Improvements in Switches for Electric Circuits, of which the following is such a full, clear, and exact description as will enable any one skilled in the art to which 10 it appertains to make and use the same, reference being had to the accompanying drawings, forming part of this specification.

The object of my invention is to simplify the construction of switches, to render the 15 same cheap to be made, and to make such switches so as to be durable as well as effective in operation.

My invention consists of an elastic spring fastened at either end, operated by a double 20 crank swiveled upon the same insulating-plate upon which the elastic spring is mounted, which latter controls means for completing the circuit between circuit-terminals arranged in co-operative proximity thereto; and it consists 25 in details of construction hereinafter to be specified, and which will be pointed out in the claims.

In the accompanying drawings, in which the 30 same letters designate the same parts throughout the various views, Figure 1 represents a side elevation of apparatus embodying my invention, showing the base and casing in cross-section. Fig. 2 represents a plan of Fig. 1 with the casing removed, looking from below Fig. 1. Fig. 3 represents a modification of 35 the apparatus in the previous figures, showing also the base and casing in section. Fig. 4 is a top view of Fig. 3 with the casing removed, and Fig. 5 is a detail view of the circuit-terminals and the circuit-completing device used 40 in the latter apparatus.

B is a metal base, upon which is mounted an insulating circular plate, p, which is bolted thereto. This plate is provided with two 45 metal pieces, b b, arranged diametrically opposite upon the plate, and between these metal pieces is an elastic spring, S, secured to the metal pieces, the latter being notched, as shown, to allow the spring to vibrate. Swiv- 50 eled at the center of the insulating-plate is a double crank, C', which is provided at its

outer end with a handle, H, for manual operation. The double crank is made of a broad piece of metal, which is cut away at its vertical portion to allow the spring S to pass 55 through it. The crank C' is shown clearly in Fig. 3. This cutting away of its vertical portion leaves two posts upon opposite sides of the spring S, between which the spring can play, and by which it is actuated. 60

Mounted loosely upon the pivot of the crank, just above the plate p, is an arm, i, of the form shown in Figs. 1 and 2, all except the end portions being below the spring S, which passes through two raised portions of 65 the same, (shown at the left hand of Fig. 2,) by which means as the spring is operated it throws the arm i into the dotted-line position shown in Fig. 2, or from this position to the position shown by full lines in the same 70 figure. Stops s s and s' s' serve to limit this arm and the crank in their movements, as will be seen by reference to the dotted and full lines in Fig. 2, which shows as well the spring S in dotted and full lines, representing 75 its two extreme positions. The ends of this arm i are upturned, as will be seen by reference to Fig. 1, and are provided with circuit-completing metallic pieces, which are adapted to pass between circuit-terminals t t 80 and t' t', secured to metallic blocks d and e, respectively, which pieces d and e are mounted upon an insulating-plate, p. The arm i may be made of conducting material or of insulating material. In the former case the 85 circuit will be completed from the terminal t to the terminal t', constituting in this case a switch for a single circuit. In case the arm i is made of insulating material, or the contacts c and c' are insulated therefrom only, 90 which would be the same thing, the springs t t and t' t' would be insulated from each other and each connected with the terminals of its own circuit, in which event the apparatus would constitute a double-pole switch 95 without departing from the spirit of my invention.

The operation of my apparatus will be understood from the foregoing, and needs, therefore, no further explanation.

In the modification illustrated in Figs. 3, 4, and 5 the arm i, carrying the circuit-com-

pleting means, is dispensed with, and the contact-maker *c* is attached directly to the spring *S* by means of screws which take into the circuit-completer *c*, and whose heads grip the spring. This construction is shown in the detail view, Fig. 5. The metal piece *d* in the modification is raised above the metal piece *e*, both of which carrying the circuit-springs *t* and *t'*, respectively, which form the terminals of the circuit.

In the construction shown in the modification the elastic spring *S*, the double crank for operating it, and all other adjuncts other than those excepted above are preserved, and the parts are provided with a casing, *C*, for housing the apparatus, as in the first form described.

I may use other means than the double crank for actuating the spring *S*, and do not wish to strictly confine myself to the employment of such means for its operation. So, too, the other parts of the construction shown may be varied without departing from the substance of my invention.

It will be observed that the contacts are established and broken in my apparatus with a quick snapping action—a thing very desirable in switches, inasmuch as the duration of the spark is greatly lessened by the almost instantaneous withdrawal of the contacts from each other, this action occurring when the spring *S* has passed its dead-point—a point between its extreme positions and midway between the same—after passing which point the elasticity of the spring actuates the parts independently of the means of manipulation.

I reserve the right in practice to make all those changes that fall within the scope of what I now desire to claim and secure by Letters Patent, which is—

1. A switch for an electric circuit, embodying a spring-plate secured at each end, a double crank embracing and directly acting upon said spring, and circuit-completing means operated by said spring for controlling electric terminals.

2. A switch for an electric circuit, consisting of a spring secured at each end and mounted upon an insulating-base, a double crank swiveled in said base and embracing said spring and acting directly upon it, circuit-completing means operated by the latter, and circuit-terminals arranged in co-operative position thereto and controlled by the aforesaid circuit-completing means.

3. A switch for electric circuits, embodying, essentially, an elastic spring secured at each end, circuit-controlling devices operated by

said elastic spring, and a handle embracing and directly manipulating the latter to govern the electrical connections.

4. A switch for electric circuits, consisting of an elastic spring secured at each end, a handle embracing said spring, a circuit-completing arm actuated solely by the movements of said spring, and circuit-terminals arranged in the path of said circuit-completing arm.

5. A switch for an electric circuit, consisting of an elastic spring secured at each end, a double crank swiveled in an insulating-base embracing and directly governing said spring, an arm carrying circuit-completing devices journaled on the pivot of said crank, directly actuated by the aforesaid spring, and circuit-terminals arranged in co-operative position to said circuit-completing devices upon the arm for controlling the circuit-terminals when the spring is manipulated.

6. A switch for an electric circuit, consisting of an elastic spring secured at each end, a handle embracing said spring, an insulating-arm carrying circuit-completing devices at the ends actuated solely by the movements of said spring, and two sets of circuit-terminals arranged in the path of said arm.

7. A switch consisting of an elastic spring secured at each end and mounted upon an insulating-plate upon a base, a double crank swiveled upon said plate and embracing said spring for directly operating the same, with a handle upon its outer end for manipulation, circuit-completing means controlled by said spring, electric terminals for co-operation with said circuit-completing means, and a casing for housing the apparatus.

8. A switch for electric circuits, consisting of an elastic spring secured at each end and mounted upon an insulating-plate upon a base, a double crank swiveled upon said plate and embracing said spring for directly operating the same, with a handle upon its outer end for manipulation, an arm carrying circuit-completing means at each end operated by said spring and journaled about the pivot of the aforesaid crank, electric terminals for co-operation with said circuit-completing means upon the arm, and a casing for the apparatus carried by the base.

In testimony whereof I have hereunto set my hand, this 20th day of September, 1886, in the presence of the two subscribing witnesses.

CLARENCE CANFIELD STIRLING.
